VENTILATING APPARATUS

Friedrich Honerkamp, New York, N. Y., assignor to
Anemostat Corporation of America, New York, N. Y.,
a corporation of Delaware

Application February 3, 1950, Serial No. 142,317

9 Claims. (Cl. 98—40)

This invention relates to ventilating apparatus, and has particular reference to the combination with an obstruction to the flow of a stream of air, of means to guide the air stream in a desired manner about the obstruction.

In the ventilating art there frequently are encountered conditions where an air outlet device must of necessity be mounted in such relationship to a member, such as a beam, a wall offset, a light fixture or the like, that the member serves to obstruct air flowing from the device and thereby prevents the air from following a most effective ventilating path of flow. Alternatively, there frequently are encountered conditions where a member, such as a light fixture or the like, must of necessity be mounted in such relationship to an already installed air outlet device as to obstruct flow of air from the latter and prevent the air from following a most effective ventilating path of flow.

The object of the present invention is to combine with an obstruction of any kind to the flow of air from an air outlet device, means to guide the air in a desired manner about the obstruction so as to, in effect, eliminate interference of the obstruction with flow of the air in a most effective ventilating path.

With the foregoing general object in view, the invention consists in the novel combination and arrangement of air flow control means relative to an obstruction to flow of air from an air outlet device, as will be herein-after more fully described, illustrated by way of example in the accompanying drawings and defined in the appended claims.

In the accompanying drawings, wherein like characters of reference denote corresponding parts in the different views:

Figs. 1, 2, 3 and 4 are sectional views illustrating different adaptations of means to cause air delivered from an air outlet device to flow in a desired manner about an obstruction to the natural path of flow of the air from the outlet device.

Referring to the drawings in detail, 10 designates a wall of a room or other enclosure, 11 designates an air outlet device which may be mounted either in the wall 10, as shown, or, if desired, adjacent thereto, for delivering air from an air supply duct (not shown) into the room or enclosure for heating, cooling, ventilating or any other purpose and in such manner that a large proportion of the air travels along the wall 10, due to certain extent to its natural tendency to cling to said wall, and 12 designates a member, such as a beam, a wall offset, a light fixture or the like, which projects from said wall 10 and acts as an obstruction to the natural path of flow of the air along said wall.

In most instances where a member, such as the member 12, obstructs flow of air along a wall from an air outlet device, it serves to deflect the air away from the wall and prevents the air from following a path which best adapts it to serve its purpose. In other words, in most instances where a member obstructs flow of air from an air outlet device along a wall, it usually is desirable that

2

the air continue to flow along the wall at the side of the member remote from the air outlet device. Accordingly, the present invention consists in the use of a vane or vanes 13 at a corner or corners of the member 12 for directing air around said member and thus, in effect, eliminating said member as an obstruction to flow of the air in a path best adapting it to accomplish its purpose.

In Fig. 1 of the drawings the wall 10 may be presumed to be either a ceiling or a side wall, the air outlet device 11 is of a type which is mounted in a recess in said wall and acts to cause a large proportion of the total amount of air delivered therefrom to flow along said wall, and the member 12 may be presumed to be either a beam, a light fixture or the like extending downwardly from said wall, or a column, offset or the like projecting inwardly from said wall in the path of flow of air from the air outlet device 11. In the absence of means to direct the air around the member 12, said member would intercept the air and deflect it away from the wall 10, with the result that there would be no flow of air from the device 11 along the wall at the side of the member 12 remote from said device 11. In fact, deflection of the supplied air by the member 12 away from the wall 10, would induce, at the side of the member 12 remote from the device 11, flow of enclosure air in the same general direction as the direction of flow of the deflected supplied air. Now assuming that the air delivered by the device 11, in order best to serve its purpose, should pass around the member 12 and continue its original direction of flow along the wall 10 at the side of said member 12 remote from said outlet device, the present invention consists in mounting a vane 13 adjacent to each of the two front corners, 14, 14 of said member 12 to cause the applied air to flow in this desired manner.

The vanes 13 may be of any suitable lengths and are of substantially L-shape in cross section so that each includes two flanges 15, 15 which are disposed at substantially right angles to each other and which preferably are joined together by a rounded corner 16. In mounting said vanes adjacent to the front corners 14, 14 of the member 12, one flange 15 of each vane is spaced from and disposed substantially parallel to the front face of the member 12 in overlapping relationship thereto, and the remaining two flanges 15 of said vanes are spaced from and disposed substantially parallel and in overlapping relationship to the two side faces, respectively, of said member 12. Thus, said vanes 13 cooperate with the member 12 to provide passageways 17 which extend around the front corners 14, 14 of said member and which cross sectionally, are open at their ends for flow of air into and from the same. It will thus be apparent that air flowing from the air outlet device 11 along the wall 10 toward the member 12 and deflected away from said wall by the side face of said member 12 nearer said air outlet device, will pass through the passageway 17 at the front corner 14 of said member 12 nearer said outlet device and will have its direction of flow changed by the vanes of the member 13 located at said corner of said member 12 so that the air then will flow substantially parallel to and across the front face of said member 12. The air then will pass through the passageway 17 at the front corner 14 of the member 12 remote from the air outlet device 11 and again will have its direction of flow changed by the vanes of the member 13 located at the latter corner 15 of said member 12 so that the air then will flow along the side face of the member 12 remote from the air outlet device 11 toward the wall 10, by which it will be intercepted and again directed in its original direction of flow along said wall. As a result, the member 12 will, in effect, be eliminated as an obstruction to the path of flow of the air from the air outlet device 11 along the wall 10,

as will be apparent from the arrows *a* which indicate the path of flow of the air around said member 12.

Should the member 12 be of shallow depth and project only a short distance from the wall 10, it may not be necessary to employ a vane 13 at the front corner 14 of said member 12 remote from the air outlet device 11 to direct the air along the remote side of said member 12 toward the wall 10. In that event only a single vane 13 located at the front corner 14 of said member 12 nearer the air outlet device 11 need be employed to direct the air across the front face of said member 12.

In instances where the side of the member 12 nearer the air outlet device 11 is of a nature such that it might act to deflect the supplied air in most any direction, or directions, or might even permit the supplied air to enter said member, as, for example, in instances where said member is in the form of a light fixture or the like having irregular sides possibly open at certain points, as illustrated in Fig. 2 of the drawings, it may be desirable also to employ a vane 13^a similar to one of the vanes 13 at the corner 18 between the wall 10 and the side face of said member 12 nearer the air outlet device 11 to assist in directing air delivered from said air outlet device around said member 12. Should a vane 13^a be employed at said corner 18, it may be mounted, as shown, with one of its flanges 15^a disposed against and extending substantially parallel to the wall 10 and with the other of its flanges 15^a disposed either against or adjacent to and extending parallel or substantially parallel to the said side face of the member 12. Thus, said vane 13^a obviously will serve to deflect the supplied air forwardly from the wall 10 along the said side face of the member 12 so that it will be substantially unaffected by any irregularity of said side face and will be acted upon by the vane or vanes 13 at the front corner or corners of the member 12 in the same manner as set forth in connection with Fig. 1 of the drawings. A companion vane 13^a may, if desired, be mounted in the same manner as said first mentioned vane 13^a at the corner 18 between the wall 10 and the side of the member 12 remote from the air outlet device 11 to assist in promoting flow of supplied air around said member 12, particularly in instances where a vane 13 is provided at the front corner of the member 12 remote from the air outlet device 11 to cause the supplied air to flow along the far side face of said member 12 toward the wall 10.

In some instances the member 12, instead of being of rectangular shape in cross section, as shown in Figs. 1 and 2 of the drawings, may be of substantially V-shape in cross section as shown in Fig. 3 of the drawings. In that event, only a single vane 13^b of substantially V-shape in cross section need be employed to direct air supplied from the air outlet device 11 around said member 12. In other words, a single vane 13^b of substantially V-shape in cross section may be mounted at the apex of the member 12 with its flanges 15^b, 15^b spaced from and extending substantially parallel to the inclined side faces, respectively, of said member 12 to provide a passageway 17^b which cross sectionally is open at its ends and extends around the apex of said member 12, as illustrated in Fig. 3. Air deflected forwardly from the wall 10 by the inclined side face of the member 12 nearer the air outlet device 11 will pass through the passageway 17^b and by the vanes of the member 13^b will have its direction of flow changed so that it will flow along the inclined side face of said member 12 remote from the air outlet device 11 toward the wall 10 to continue its original direction of flow along said wall. If desired, other vanes may be employed at the corners between the wall 10 and the inclined side faces of the member 12 illustrated in Fig. 3 in the same manner as the vanes employed at the corresponding corners in the example of the invention illustrated in Fig. 2 of the drawings to assist in directing the air around a member 12 such as is illustrated in Fig. 3.

Fig. 4 of the drawings illustrates the utility of the in-

vention as applied to a baggage rack or similar member 20 projecting inwardly from a side wall of an enclosure such as a railway car, an aircraft cabin, a motor bus or the like designated generally as 21. The air outlet device 11 is illustrated as being mounted as usual in the ceiling 22 of the enclosure so as to direct air across the ceiling toward and downwardly over the side wall 23 of the enclosure. The member 20 acts, of course, as an obstruction to downward flow of the air over the side wall 23 and serves to deflect the air inwardly so that ordinarily the air would not reach the side of the enclosure beneath said member 20. However, in accordance with the present invention, a vane 13^c of substantially U-shape in cross section is mounted in spaced relationship to the inner edge of the member 20 to provide a passageway 17^c of substantially U-shape in cross section extending around the inner edge of said member 20. Said passageway, considered cross sectionally, is open at its ends for flow of the air therethrough, and the upper portion of the vane 13^c is disposed to intercept air flowing inwardly across the top of the member 20 and to direct it through said passageway 17^c. The air thus is caused to flow across the under side of the member 20 toward the side wall 23 of the enclosure so as to reach the space beneath said member 20.

The vane or vanes used in any particular instance may, of course, be formed from metal, glass, plastic, or any other suitable opaque, translucent or transparent material.

From the foregoing description considered in connection with the accompanying drawings, it is believed that the invention will be clearly understood and its advantages appreciated. It is desired to emphasize, however, that the illustrated adaptations of the invention are merely by way of example and are not to be construed as limiting, since the invention within its spirit and scope as defined in the appended claims, may readily be adapted to the solution of many other air flow control problems encountered in the ventilating art.

I claim:

1. In ventilating apparatus including a device for delivering air into an enclosure past an obstruction in the intended path of flow of air from said device, said obstruction having a corner, a vane of substantially L-shape in cross section mounted in spaced relationship to and extending around the corner of said obstruction to guide the air around said corner.

2. In ventilating apparatus including a device for delivering air into an enclosure past an obstruction to the intended path of flow of air from said device, said obstruction having a plurality of corners, a plurality of vanes of substantially L-shape in cross section mounted in spaced relationship to and extending around different corners, respectively, of said obstruction to guide the air around said obstruction back to its intended path of flow.

3. In ventilating apparatus including a device for delivering air into an enclosure adjacent to and along a wall of the enclosure past a member projecting from the wall into the enclosure and constituting an obstruction to the intended path of flow of air from said device along said wall, said member having side faces and a front face and corners at their junctions and said side faces in conjunction with the face of said wall forming other corners, a pair of vanes of substantially L-shape in cross section, each including angularly related flanges, mounted adjacent to the corners at the junction of opposite side faces of said members with said wall face with their flanges disposed adjacent to and extending substantially parallel to said wall face and said side faces, respectively, and another pair of similar vanes mounted adjacent to the corners at the junctions of the side faces with the front face of said member with their flanges spaced from and extending substantially parallel to said side faces and said front face, respectively, to direct the air around said member back to its intended path of flow.

70 75

along said wall at the side of said member remote from said device.

4. In ventilating apparatus including a device for delivering air into an enclosure adjacent to and along a wall of the enclosure past a member projecting from the wall into the enclosure and constituting an obstruction to the intended path of flow of air from said device along said wall, said member having angularly related faces forming a corner, a vane of substantially L-shape in cross section, including angularly related flanges, mounted adjacent to said corner with said flanges disposed substantially parallel to and spaced from said faces, respectively, to direct the air around said corner.

5. In ventilating apparatus including a device for delivering air into an enclosure adjacent to and along a wall of the enclosure past a member projecting from the wall into the enclosure and constituting an obstruction to the intended path of flow of air from said device along said wall, said member having side faces which in conjunction with the face of said wall form corners and a front face which in conjunction with said side faces form corners, a vane of substantially L-shape in cross section including angularly related flanges mounted in the corner at the junction of said wall face with the side face of said member nearer said device with its flanges disposed adjacent to and substantially parallel to said faces, respectively, to direct the air along the side face of said member nearer said device, and another vane of substantially L-shape in cross section extending around the corner of said member nearer said device with its flanges spaced from and extending substantially parallel to the front face and to the side face of said member nearer said device, respectively, to direct the air around said corner across the front face of said member.

6. In ventilating apparatus as set forth in claim 5 a third vane of L-shape in cross section extending around the corner of the member remote from the air delivering device with its flanges spaced from and extending substantially parallel to the front face and to the side face of the member remote from the air outlet device, respectively, to direct the air from the front face of the member around the corner of the member remote from the air outlet device.

7. In ventilating apparatus including a device for delivering air into an enclosure adjacent to and along a wall of the enclosure past a member projecting from the wall into the enclosure and constituting an obstruction to the intended path of flow of air from said device along said wall, said member having side faces and a front face and corners at their junctions, a pair of vanes of substantially L-shape in cross section extending around said corners in spaced relationship thereto, respectively, to guide the air about said member and toward said wall at the side of said member remote from said air outlet device.

8. In ventilating apparatus including a device for delivering air into an enclosure past a member disposed in the path of flow of air from said device, said member having angularly related faces forming a corner, one of said faces being disposed to intercept air delivered from said device and to deflect it from its normal path of flow from said device, a vane of substantially L-shape in cross section extending around said corner in spaced relationship thereto for guiding the deflected air around said corner, said vane having angularly related flanges one of which is disposed to intercept air deflected by the air intercepting face of said member.

9. In a ventilating installation wherein an air supply device is effective to deliver air into a room and there exists in the room an obstruction which lies in the intended direction of flow of air from the device and deflects the air from its intended direction of flow beyond said obstruction, vane means mounted adjacent to said obstruction in the path of flow of the air deflected by said obstruction and effective to intercept and guide the deflected air around said obstruction back to its intended direction of flow beyond said obstruction.
